UNITED STATES PATENT OFFICE.

LEWIS C. MCADAMS, OF LOS ANGELES, CALIFORNIA.

RAILWAY SWITCH.

Application filed October 28, 1920. Serial No. 420,285.

To all whom it may concern:

Be it known that I, LEWIS C. MCADAMS, a citizen of the United States, and a resident of Los Angeles, in the county of Los Angeles and State of California, have invented new and useful Improvements in Railway Switches, of which the following is a specification.

This invention relates to railway switches, for use on steam and electric railways, so as to regulate and effect the opening and closing of the switch as a car or train approaches the switch intersection. The main object of my invention is to provide a device of the character stated, whereby the car or train when approaching the switch may actuate the switch in either direction by means of manually controlled mechanism adapted to be operated by the motorman or engineer of the train or car, so as to eliminate the necessity of stopping the car and for the operator to leave his car as is customary with other devices at the present time, for actuating the switch.

It is a further object of this invention to provide a switch actuating mechanism which may be readily installed between the rails of a street or steam railway and completely housed so as to prevent water and other elements from coming in contact with and rendering the actuating mechanism inoperative.

A still further object of this invention is to provide a simple, compact, and effective device for the purpose stated which may be installed by unskilled persons and operated without inconvenience to the operator and with dispatch, so as to facilitate the operation of the cars or train over the track at all times. Heretofore a type of electric switch has been generally employed, especially with electric car systems, and such devices unsatisfactory because of the complexity of the mechanism and a great deal of trouble in the operation and use thereof.

has been encountered; it is therefore a further object of my invention to provide a mechanism which is incapable of being affected in the manner stated and which lacks complexity and makes for simplicity and efficiency in operation.

Another object of my invention is to provide a switch mechanism of the character and for the purpose stated whereby the cars or train moving over a track may actuate

the switch in either direction, separate operating means being provided for operating the switch in each direction and a common operating member being connected with a movable switch point and with each of said operation units. Other objects will appear as the description progresses.

I accomplish the above objects by means of the mechanism illustrated in the accompanying drawing, in which:

Fig. 1 is a plan view of a railway switch with my actuating means installed between the rails thereof and operatively connected therewith.

Fig. 2 is a longitudinal sectional elevation of one of the operating units.

Fig. 3 is a transverse sectional elevation of the same, on line 3—3.

Fig. 4 is a fragmentary view of one corner of the housing for the same.

Fig. 5 is a fragmentary section of the same on line 5—5.

Fig. 6 is a perspective view of one of the operating members inclosed as shown in Fig. 2.

Fig. 7 is a plan view of the device shown in Fig. 2 with the top removed.

Fig. 8 is a plan of the same showing a removable and resilient form of actuating top applied to the casing and adapted to be engaged by an operating member attached to a car or train.

Fig. 9 is a plan view, with the top removed, of a housing inclosing an auxiliary operating mechanism common to the car-operated units and adapted to be connected with the movable switch point for operation.

Fig. 10 is a longitudinal sectional elevation of the same.

Fig. 11 is an enlarged sectional elevation showing the operative connections between the individual car-operated unit and the common or intermediate operating mechanism shown in Fig. 9 and Fig. 10.

Having in mind the above objects I have illustrated one practical embodiment of my invention in the drawings appended hereto which I will now describe in detail.

Briefly stated my invention embodies a pair of spaced operating units A and B arranged between the rails r , r , of the track and another unit C positioned at a point close to the switch point S. Units A, B and C have housings H, H', and H'', respectively,

and the housings H, H' are connected with housing H'' by means of pipes or conduits P and P', respectively, so as to prevent the entrance of dirt and water to the operating mechanism contained in said housings and hereinafter described.

Housings H and H' of units A and B each have a primary operating member O pivotally held on trunnions t, t in grooves 1, 1 10 formed in the sides thereof, and on operating arm O' similarly pivoted by means of trunnions t', t' in grooves 2, 2 at the rear of member O. The arms O' extend substantially forwardly of the fulcrums of members O, are curved and have their front ends resting in grooves 3 formed in the top side 15 of the members O. Tops T of thin sheet metal of resilient character are provided for covering the housings H and H' and are 20 mounted on spiders 4 adapted to be secured to the flanges 5 formed on the upper portion of the said housings and held thereon by means of bolts 5'. A plurality of flat springs 6, 6 are attached to the spiders 4 and have 25 their free ends engaging the lower surface of the tops T so as to cause the horizontal portions of said tops to be normally upwardly extended. The curved central portions of members O' are adapted to engage the lower 30 surfaces of said tops, and the area of said tops is such that a maximum degree of resiliency will be afforded for insuring the proper operation of the arms O' and members O. Rollers 7, or other suitable devices, 35 carried on and depending from the cars adapted to pass over the tracks on which my system is installed, are provided for engagement with the tops T, as shown in Fig. 2, there being one of said devices for each 40 of the units A and B. The operation of said devices so as to lower them into position for engagement with the tops T will serve to depress the central portions of the tops and correspondingly depress the members O', and thus swing the members O by 45 means of the connection between said members previously described.

The lower portions 9 of members O are bifurcated so as to receive and pivotally hold 50 the rear ends 10 of operating rods R and R' which are housed in the pipes P and P', respectively, and the movement of the members O and O' as described will correspondingly move the said rods longitudinally of 55 said pipes.

Unit C has a wheel W therein having trunnions 11, 11 on opposite sides thereof and rollers 12, 12 held on said trunnions and adapted to be held in slots 13 formed in 60 guide plates G and G' attached at their ends to the sides of the housing H'' of said unit, as shown in Fig. 9. The forward ends 14, 14 of rods R and R' have links L and L' attached thereto, respectively, and said links 65 are also connected with eye bolts 15, 15

held at diametrically opposite points on and near the periphery of the operating wheel W, as shown in Fig. 11.

Thus, the longitudinal movement of the rod R will rotate the wheel W slightly in a given direction and said wheel will also be caused to reciprocate in the housing H'' by means of the movement of the rollers 12, 12 in the slots 13 on the guides G and G'. The operation of rod R' will actuate the wheel W in a reverse direction and to a corresponding extent and the said wheel will remain in the position to which it may have been previously moved until the other rod shall have been operated. Thus, also, the operation of either of the units A or B will restore the other unit to normal position.

The movable switch point S is operatively connected with the operating wheel W by means of a rod 16 which has its inner end 17 suitably connected with the said wheel, as shown in Figs. 9, 10 and 11, and the operations of the units A and B will likewise actuate the switch point S by means of the connections described for opening or closing the switch as the case may be.

In operation, when a car approaches the switch from the left as shown in the drawings, for instance and it is desired that the car should take the switch, the motorman or engineer will depress the switch operating device on the car so as to engage the unit A and depress the resilient top T thereof. This will effect the operation of the members O and O', connecting rod R, wheel W, 100 connection rod 16 and switch point S, the latter being closed into the position shown in Fig. 1 so that the car may pass over the rails r, r of the switch. Should it be desired to pass a car by the switch over the rails r, r of the straight track, the unit B is operated in a similar manner for moving the switch member S in a reverse direction, thus opening the switch and clearing the track straight ahead.

In the operation of the tops T the buckling tendency of sheet metal is employed for operating the switch members and the addition of the springs for engagement with said tops serves to insure the restoration of the 115 tops to their upwardly extended position. It will be observed that my mechanism is free from all complications and useless parts and is thus capable of extended use without attention and may be installed and maintained at a minimum of expense.

What I claim is:

1. A railway switch actuating device comprising in combination with the parallel tracks, of a railway and a movable switch member interposed in one of said tracks, a pair of spaced housings between said tracks substantially spaced from said switch member, and a central housing opposite said switch member, separate pipes connecting 125

- said central housing with said other housings, a disc rotatably mounted on a vertical axis in said central housing and operably connected with said switch member, cranks mounted in said other housings on horizontal axes and operably connected with said disc, and means in said spaced housings adapted to be operated by a car for operating said cranks when said car is moved thereover in opposite directions, for correspondingly moving said switch member, said means including arms pivoted in said housings and having their free ends resting loosely upon portions of said cranks.
- 10 2. A railway switch actuating device comprising in combination with the parallel tracks of a railway, and a movable switch member interposed in one of said tracks, a pair of spaced housings between said tracks substantially spaced from said switch member, and a central housing opposite said switch member, separate pipes connecting said central housing with said other housings, a disc rotatably mounted on a vertical axis in said central housing and operably connected with said switch member, cranks mounted in said other housings on horizontal axes and operably connected with said disc, and means in said spaced housings adapted to be operated by a car for operating said cranks when said car is moved thereover in opposite directions, for correspondingly moving said switch member, said means including arms pivoted in said housings and having their free ends resting loosely upon portions of said cranks, and resilient sheet metal covers on said housings adapted to rest upon and for actuating said arms.
- 15 3. A railway switch actuating device comprising in combination with the parallel tracks of a railway and a movable switch member interposed in one of said tracks, a pair of spaced housings between said tracks substantially spaced from said switch member, and a central housing opposite said switch member, separate pipes connecting said central housing with said other housings, a disc rotatably mounted on a vertical axis in said central housing and operably connected with said switch member, cranks mounted in said other housings on horizontal axes and operably connected with said disc, and means in said spaced housings adapted to be operated by a car for operating said cranks when said car is moved thereover in opposite directions, for correspondingly moving said switch member, said means including arms pivoted in said housings and having their free ends resting loosely upon portions of said cranks, and resilient sheet metal covers on said housings adapted to rest upon and for actuating said arms, the connections between said disc and said cranks including rods pivotally connecting said members and effecting a cranking movement thereof.

LEWIS C. McADAMS.
